United States Patent Office

Des. 217,637
Patented May 19, 1970

217,637

LIGHT FIXTURE

Buell Moore, Houston, Tex., assignor to Esquire, Inc.,
New York, N.Y., a corporation of Delaware

Filed Apr. 10, 1969, Ser. No. 16,662

Term of patent 14 years

Int. Cl. D26—03, 02

U.S. Cl. D48—31

FIG. 1

FIG. 2

FIG. 3

FIG. 1 is a perspective view from the bottom and one corner of a light fixture incorporating my design;

FIG. 2 is a perspective view from the top and opposite corner of such light fixture; and

FIG. 3 is a bottom view of said light fixture.

The smooth surfaces on the sides and bottom of said light fixture are windows.

I claim:

The ornamental design for a light fixture, substantially as shown and described.
